DESIGN FOR A CAP FOR CONTAINERS

Lindsay Thorne Crabbe, Chicago, Ill., assignor to Phoenix Metal Cap Co., Inc., Chicago, Ill.,
a corporation of Illinois

Application January 11, 1940, Serial No. 89,403

Term of patent 14 years

To all whom it may concern:

Be it known that I, Lindsay T. Crabbe, a citizen of the United States, residing at Chicago, Cook county, State of Illinois, have invented a new, original, and ornamental Design for a Cap for Containers, of which the following is the specification, reference being had to the accompanying drawing, forming a part thereof.

In the drawing:

Fig. 1 is a top plan view of the cap showing my new design.

Fig. 2 is a side elevation.

Fig. 3 is a vertical sectional view taken through the center of the cap; and

Fig. 4 is an enlarged detail top plan view of a portion of the cap.

I claim:

The ornamental design for a cap for containers, as shown.

LINDSAY THORNE CRABBE.
